UNITED STATES PATENT OFFICE.

JAMES S. RAGAINS, OF OTTUMWA, IOWA.

WATER-PRESSURE SYSTEM.

1,263,287.

Specification of Letters Patent. Patented Apr. 16, 1918.

Application filed March 12, 1917. Serial No. 154,089.

To all whom it may concern:

Be it known that I, JAMES S. RAGAINS, a citizen of the United States, residing at Ottumwa, in the county of Wapello and State 5 of Iowa, have invented certain new and useful Improvements in Water-Pressure Systems, of which the following is a specification.

This invention relates to certain new and 10 useful improvements in water pressure systems, and especially to that type adapted for country homes, and it consists in an improved combined air and water tank arranged in the water of the well, together 15 with an air pressure supply and a water lead both connected to the tank in the well.

The invention further resides in the features of construction, the arrangements and combinations of parts hereinafter described 20 in detail and succinctly defined in the appended claims, reference being had to the accompanying drawing wherein like numerals of reference designate like parts and

Figure 1 is a diagrammatic view illustrating the improved water pressure system 25 in its practical embodiment; and

Fig. 2 is a vertical section of the combined air and water tank.

Referring more in detail to the drawing, 30 the numeral 1 designates an air pump, of any desired or suitable type, having communication with a pressure storage tank 2 for supplying compressed air thereto for the purpose hereinafter referred to.

The combined air and water tank 3 is 35 arranged in the water at the lower portion of the well 4 and comprises an upper air compartment 5 which is connected to the air pressure storage tank 2 by a pipe 6, the latter having a shut-off cock or valve 7 therein for controlling the supply of air to said air compartment 5. Said tank 3 has a water compartment 8 underlying the air compartment 5 and preferably of much larger 40 capacity than said compartment, the two compartments being communicatively connected through a port 9 adapted to be closed by a valve 10, said valve being of any suitable type although a ball valve is here

50 shown. A spring 11 urges the valve to

its seat, a pin 12 serving to hold the spring in position.

The bottom wall of compartment 8 is provided with an inlet opening or port 13 adapted to be closed by a ball valve 14, 55 or other type of valve, a pin 15 extending across the inner end of the valve cage 16 to retain said valve against displacement.

A water conducting pipe 17 is connected with the water compartment at its lower 60 end, said pipe leading to the house, or other suitable points of delivery, as through faucet 18. The valves 10 and 14 both open inwardly within the water compartment 8 so that air may pass through port 9 and water 65 through inlet 13 into the water compartment 8, but said valve 10 will close against water entering the air compartment 5, and said valve 14 will close to prevent the egression of water through said port 13. Thus 70 if air is admitted into compartment 5 under pressure, the valve 10 will open and the valve 14 close to permit the air pressure forcing the water in compartment 8 out through pipe 17. 75

In practical operation the valve 7 is closed permitting fresh water to flow into the water compartment 8, the valve 10 closing to prevent passage of the liquid into the air compartment 5. It is therefore obvious that 80 no matter how deep the tank 3 may be disposed, the air compartment will always remain free of water. It will further be noted that this air compartment will serve as a float to buoy up the tank and thereby relieve 85 the piping 6 and 17 from the weight of said tank.

As soon as faucet 18 is opened, the air in compartment 5, after the valve 7 is opened, will unseat valve 10, close valve 14, and 90 force the water in said compartment 8 out of the latter through the draw-off pipe 17. Consequently, fresh and cold water direct from the well is always obtainable, and since the present system embodies but few 95 parts the same may be cheaply manufactured and durably constructed.

What is claimed is—

1. In a water pressure system, a tank adapted to be arranged in a body of water, 100

said tank comprising a floating air chamber and a communicating water chamber, the latter having valves permitting the ingress of water and air and closing against the egress of the water, means for supplying air under pressure to the air compartment, and a draw-off pipe connected to the water compartment.

2. In a water pressure system, a water compartment adapted to be immersed in a body of water and having a water inlet

controlled by an inwardly opening valve, an air compartment arranged to exert a buoying influence on the water compartment and communicating with the latter through a passage, a valve closing the passage against the flowing of water from the first compartment to the air compartment, a draw-off pipe leading from the former, and air pressure means for the air compartment. 15

20 In testimony whereof I affix my signature.

JAMES S. RAGAINS.
